UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY.

REVERSIBLE FULCRUM.

Application filed April 8, 1921. Serial No. 459,790.

Be it known that I, WILLIAM C. HEDGCOCK, a citizen of the United States, residing at Chicago, in the county of Cook and State of Illinois, have invented certain new and useful Improvements in Reversible Fulcrums, of which the following is a specification.

This invention relates to reversible fulcrum arrangements.

At the present time non-reversible fulcrums are used most, in spite of the fact that separate right- and left-hand fulcrums are required under such circumstances, because in reversible fulcrums generally used thus far the fulcrums comprise three separate members, namely, a member secured to the compression member, another member secured to the tension member, and another member interposed between said other two members. Such three-piece fulcrums have more or less lost motion between the parts, thereby lacking one very desirable feature of a fulcrum, namely, rigidity as a strut of a brake beam truss. Furthermore, where the fulcrum is made up of more than one piece, it is not so durable and is more liable to failure.

One object of my invention, therefore, is to provide a one-piece reversible fulcrum which is simple and durable in construction, efficient in operation and adapted to meet all of the requirements for successful commercial use.

Another object is to provide a simple and efficient locking connection between the compression member of a brake beam and a fulcrum.

These and other objects are accomplished by means of the arrangements disclosed on the accompanying sheet of drawings, in which—

Figure 1 is a top plan view of a brake beam and fulcrum embodying my invention;

Figure 2 is a front elevation of the same; Figure 3 is a fragmentary top plan view of my improved reversible fulcrum showing parts of the tension and compression member and means for locking the latter to the fulcrum;

Figure 4 is a view taken at right angles to the view shown in Figure 3 with the compression and tension members shown in section;

Figure 5 is a fragmentary rear elevational view showing, among other things, angle portions of the band of the reversible fulcrum adapted to engage upper and lower portions of the compression member;

Figure 6 is a reduced transverse sectional view through the loop or compression member receiving portion of the fulcrum showing upper and lower angled portions which engage the upper and lower sides of the compression member, and also showing tapered locking projections on the front wall of the loop portion;

Figure 7 is a reduced fragmentary side elevation of the compression member receiving portion of the reversible fulcrum; and

Figure 8 is a fragmentary view similar to that shown in Figure 4 showing a modification of the arrangement in which the reversible fulcrum and compression member are pivotally connected.

The various novel features of my invention will be apparent from the following description and drawings and will be particularly pointed out in the appended claims.

Referring to the figures of the drawing, it will be noted that I have disclosed my invention in connection with the truss type of brake beam, including a compression member 10 and tension member 11, which are joined at their ends and receive brake heads 12. My improved one-piece fulcrum 13 is interposed between the compression and tension members intermediate their ends, and includes three integrally formed portions, namely, the intermediate portion 14 for receiving an operating lever in slot 15, a portion 16 for receiving the tension rod 11, and a portion 17 for receiving the compression member 10. As shown, the compression member receiving portion 17 of the fulcrum is in the form of a closed band, the rear wall of which in one arrangement, for example, in Figure 4, is provided with an inwardly extending projection 18 which extends into an aperture 19 in the web 20 of the compression member whereby the fulcrum may have a pivotal movement in being reversed and at the same time be held in position with respect to the compression member.

In Figure 8 of the drawings a modifica-

tion is shown in which both the rear wall of the banded portion of the fulcrum and the web 20 of the compression member are provided with apertures through which a rivet

5 21 passes for pivotally connecting said parts, the connection being made sufficiently loose to permit a pivotal action.

The upper and lower walls, respectively, of the banded portion of the fulcrum each have angled portions which form a V, the angled portions 22 and 23 of the upper wall and the angled portions 24 and 25 of the lower wall co-operating at different times with the upper and lower flanges 26 and 27 of the compression member. As shown in Figure 5, the upper wall portion 22 and lower wall portion 24 are respectively in engagement with upper and lower compression flanges 26 and 27. If, however, the fulcrum 10 is reversed, upper wall portion 23 and lower wall portion 25 will be in engagement, respectively, with said upper and lower flanges 26 and 27 of the compression member.

For making the reversible fulcrum rigid with respect to the compression member in the different positions, wedging means has been provided. In this connection it will be noted that the front wall of the banded portion of the fulcrum is provided with six 15 inclined rearwardly extending projections 28, 29, 30, 31, 32 and 33, which cooperate with a tapered key 34, which, as shown, fits in between the front wall of the banded portion of the fulcrum and the flanges 26 and 27 of the compression member. The upper projecting portion 35 of the wedge key 34 in the position shown in the figures of the drawings, is wedged in between the inclined projections 28 and 29 on one side 20 and the upper flange 26 of the compression member on the other side, and the lower projecting portion 36 of the wedge key is wedged in between the inclined projection 33 on one side and the lower flange 27 of the compression member for making the structure rigid and at the same time the fulcrum is locked against pivotal movement as a result of the lateral wedge pin projection 37 25 interposed between the band projection 29 on one side and the ends of band projections 32 and 31 on the other side, and lateral wedge pin projection 38 interposed between the band projection 33 on one side and the ends of band projections 31 and 32 on the other side, the other wedge pin projections 39 and 40 cooperating with the inner surfaces of the compression member flanges 26 and 27. The wedge key 34 is locked in 30 securing position by one of the two locking tips 41 and 42, the latter in the figures being shown as bent over for the purpose stated. To remove the key it is merely necessary to straighten the locking tip, whereupon the wedge key may be withdrawn. It will be understood that the ful-

crum may be locked in its reverse position in a manner similar to that described hereinabove.

It will be noted that the inclined wedging projections 29, 31, 32 and 33 on the front 70 wall of the banded portion of the fulcrum are arranged in a diamond shape, open at the corners for the passage of portions of the wedge key and that other wedge projections formed on the front wall of said banded portion of the fulcrum lie outside of the diamond and in line with certain other of the projections.

The tension member receiving portion of the fulcrum has upper angled wall portions 80 43 and 44 and lower angled wall portions 45 and 46 which cooperate, respectively, with the top and bottom portions of the tension member 11 when the fulcrum 14 is in its different operative positions. These V-shaped angled tension member receiving portions at the tension end of the fulcrum correspond to the angled or V-shaped wall portions at the compression member end of the reversible fulcrum. 90

It is my intention to cover all modifications of the invention falling within the spirit and scope of the following claims.

I claim:

1. An integrally-formed reversible brake beam fulcrum including a compression member receiving portion having top and bottom angled surfaces which in different positions engage the top and bottom portions of an associated compression member, and wedge means insertable between said receiving portion and compression member for locking the fulcrum in adjusted position.

2. An integrally-formed reversible brake beam fulcrum including a compression member receiving portion having top and bottom angled surfaces which in different positions engage the top and bottom portions of an associated compression member, a wedge key having wedging means for making the connection rigid and locking means normally to prevent pivotal movement of the fulcrum.

3. An integrally-formed fulcrum including a compression member receiving portion having a plurality of walls for embracing a compression member, one of said walls having a plurality of inclined wedge projections for cooperating to lock the fulcrum member in a given position.

4. An integrally-formed reversible fulcrum including a plurality of walls for embracing a compression member, one of said walls having a plurality of wedge-shaped projections at an angle with respect to each other which are instrumental in wedging the fulcrum in place in its different operative positions.

5. An integrally-formed reversible fulcrum including a plurality of walls for em-

bracing a compression member, one of said walls having a plurality of wedge-shaped projections at an angle with respect to each other which are instrumental in wedging the fulcrum in place in its different operative positions, and a wedge key operatively associated with said projections.

6. An integrally-formed reversible brake beam fulcrum including a banded portion 10 for receiving a compression member, one wall of said banded portion having a plurality of wedged-shaped projecting portions arranged in diamond formation whereby the fulcrum may be secured in its different 15 operative positions.

7. An integrally-formed reversible brake beam fulcrum including a banded portion for receiving a compression member, one wall of said banded portion having a plurality 20 of wedged-shaped projecting portions arranged in diamond formation whereby the fulcrum may be secured in its different operative positions, and a wedge key which may occupy different positions with respect 25 to said projections for locking the fulcrum in its different operative positions.

8. An integrally-formed reversible brake beam fulcrum including a banded end for the reception of a compression member, the 30 front wall of said banded portion having a plurality of wedge shape projections arranged at an angle with respect to each other in diamond shape with the corners broken away, and a wedge key having a 35 projection which is wedged between one of said wedge projections and a portion of said compression member for forming a rigid connection and other projections on said wedge key cooperating with said wedge-shaped 40 projections and with said compression member for locking the fulcrum in adjusted position.

9. An integrally-formed reversible brake beam fulcrum including a compression member 45 receiving portion having top and bot-

tom angled surfaces which in different positions engage the top and bottom portions of an associated compression member and having a tension member receiving portion having top and bottom angled surfaces which 50 in different positions engage top and bottom portions of a tension member.

10. In a brake beam, the combination of a brake head carrying member with a receiving opening therein, and an integrally-formed reversible fulcrum having a banded portion embracing said member and provided with a projection extending into said receiving opening whereby the fulcrum may 55 be guidedly reversed.

11. In a brake beam, the combination of a brake head carrying member, and an integrally-formed reversible fulcrum having a banded portion embracing said member, said member and banded portion having 65 an interengaging pivotal connection whereby the fulcrum may be reversed with respect to said member.

12. In a brake beam, the combination of a brake head carrying member, an integrally-formed reversible fulcrum having a banded portion embracing said member, said member and banded portion having an interengaging pivotal connection whereby the 70 fulcrum may be reversed with respect to 75 said member, and wedge means for securing said fulcrum in position.

13. In a brake beam, the combination of a brake head carrying member, an integrally-formed reversible fulcrum having a banded portion embracing said member, said member and banded portion having an interengaging pivotal connection whereby the 80 fulcrum may be reversed with respect to 85 said member, and means for securing said fulcrum in position.

Signed at Chicago, Illinois, this 31st day of March, 1921.

WILLIAM C. HEDGCOCK.
